UNITED STATES PATENT OFFICE

FREDERICK D. PENNEY, OF LOS ANGELES, CALIFORNIA

METHOD OF PRODUCING ORNAMENTAL MATERIAL FOR LAMP SHADES AND THE LIKE

Application filed May 22, 1929. Serial No. 365,005.

The invention relates to an improved method for producing ornamental material for lamp shades and the like and has for its object the production of a material of this character which is highly ornamental and semi-translucent.

Another object of the invention is the provision of a process by means of which ornamental material of the class indicated may be produced economically.

Another object of the invention is the provision of a method of the character indicated by means of which ornamental material especially adapted for use in making lamp shades may be readily produced having highly artistic appearance and of semi-translucent character.

Other objects will appear hereinafter.

The invention consists in the method of procedure hereinafter described and claimed.

The invention will be best understood by reference to the accompanying drawings forming a part of this specification, and in which

Fig. 1 is a face view of one of a plurality of stencils employed in the process,

Fig. 2 is a similar view of another stencil employed in the process,

Fig. 3 a section taken substantially on line 3—3 of Fig. 1,

Fig. 4 a section taken substantially on line 4—4 of Fig. 2,

Fig. 5 a face view of a sheet of the material to be ornamented with the design from the stencil of Fig. 1 placed thereon, and

Fig. 6 a similar view of said sheet of material with the composite designs produced by both the stencils of Fig. 1 and Fig. 2 placed thereon.

A preferred application of the process comprises the cutting of a sheet of high-grade parchment paper into desired shape for use as a portion or panel of a lamp shade or the like.

The design desired is applied to said sheet preferably by the use of reversed stencils, a separate stencil being employed for each of the differently colored designs applied. In Figs. 1 and 2 I have illustrated two of such stencils. The stencil 10, illustrated in Fig. 1, is provided with a plurality of stencil open-

ings 11, 12, 13 and 14 cut therethrough in various designs as indicated, the particular designs representing roughly blossoms or flowers of a plant. The stencil 15, illustrated in Fig. 2, has cut therethrough stencil openings 16 and 17, roughly in the form of the leaves of the plant, and stencil openings or lines 18, roughly in the form of stems or branches of the plant.

The designs thus provided for are applied to a sheet 19 of the parchment paper cut in the shape indicated by successively placing said stencils over said sheet and spraying differently colored lacquer enamels onto said sheet through said stencils by means of an air brush. In the form of design illustrated, a red color is used in conjunction with the stencil 10 and the blossom designs 11', 12', 13' and 14', corresponding with the stencil openings 11, 12, 13 and 14, are thus placed upon the sheet 19 in red enamel color. Subsequently, the Figs. 16', 17' and 18' are superposed upon the sheet 19 by similarly spraying through the stencil 15 with green colored lacquer enamel, thus making a composite design, as indicated in Fig. 6.

After the composite design has thus been applied to the sheet 19, the said sheet is then placed in a bath consisting of a solution of four parts of boiled linseed oil and one part of paraffin wax. The oil should be boiled and the paraffin dissolved. The sheet is permitted to soak in this solution for a period of twelve hours.

This solution will have the effect of waterproofing the material and rendering the same semi-translucent.

The sheet is then removed from the oil-paraffin solution and placed in cold water for a period of four minutes. After its removal from the cold water, the sheet is then crackled by rolling, bending and crumpling into a ball until the desired soft texture is produced. By placing the material in cold water, it is softened to such an extent as to make it easier to crackle and emboss. A further result by this treatment is that the cracks which are produced in crackling are smaller and finer than when the crackling is

done immediately after removal from the oil bath.

While the sheet is still damp, the same stencils as were used in spraying the designs thereon are again successively applied to the sheet and the sheet and stencil pressed together by rubbing a dull, blunt instrument over the edges of the stencil until the design thereof is raised above the surface of the sheet. Each stencil employed in applying the composite design to the sheet is thus employed until the composite design will thus be raised or embossed on the sheet. The embossing produced by the first stencil is not flattened by the second one, because the stencil is made of a light material known as fibre board, and because the only place where pressure is applied is at the openings in the stencil. After the embossing process, the sheet is spread out on a flat surface and permitted to dry. If a soft leather effect is desired, before the sheet is thoroughly dried the same is given a coat of lacquer. If a hard stiff surface is desired, a coat of melted, chipped glue is applied to the back of the sheet and the coat of lacquer applied after the glue. After the last-mentioned coat of lacquer has dried, a coat of antique color mixture of raw umber, turpentine and Japan 30 dryer is sprayed over the face of said sheet and permitted to partially dry. When partially dry, the last-mentioned coat is partially rubbed off and while still wet rotten stone powder is first rubbed over the surface and then wiped off from the surface of the sheet. The sheet is then permitted to dry and is ready for use.

The ornamental material thus provided will be found to be highly useful and ornamental in making ornamental lamp shades or for similar purposes.

While I have illustrated and described the preferred steps for carrying on the process, this is capable of variation and modification without departing from the spirit of the invention. I therefore do not wish to be limited to the precise details disclosed, but desire to avail myself of such variations and modifications as fall within the scope 50 of the appended claims.

Having thus fully described my invention, what I claim as new and desire to secure by Letters Patent is:

1. The method of producing ornamental material which consists in forming a design in color upon a sheet of porous material by the use of a stencil; soaking said sheet in a water proofing solution; pressing said sheet and stencil together to emboss the design on said sheet; and then drying and preparing said sheet for use.

2. The method of producing ornamental material which consists in forming a design in color upon a sheet of porous material by the use of a stencil; soaking said sheet in a

solution consisting of boiled linseed oil and paraffin; pressing said sheet and stencil together to emboss the design on said sheet; and then drying and preparing said sheet for use.

3. The method of producing ornamental material which consists in forming a design in color upon a sheet of the desired material by the use of a stencil; pressing said sheet and stencil together to emboss the design on said sheet; and then drying and preparing said sheet for use.

4. The method of producing ornamental material which consists in forming a design in color upon a sheet of porous material by the use of a stencil and lacquer enamel; soaking said sheet in a solution of boiled linseed oil and paraffin; pressing said sheet and stencil together to emboss the design on said sheet; and then drying and preparing said sheet for use.

5. The method of producing ornamental material which consists in forming a design in color upon a sheet of parchment paper by the use of a plurality of stencils and lacquer enamels; soaking said sheet in a solution of boiled linseed oil and paraffin; placing the sheet in cold water temporarily; then working and crumpling the sheet to soften the same; then, while the sheet is still damp, successively pressing said sheet and said stencils together to emboss the design on said sheet; and then drying and preparing said sheet for use.

6. The method of producing ornamental material which consists in forming a design in color upon a sheet of parchment paper by the use of a plurality of stencils and lacquer enamels; soaking said sheet in a solution of boiled linseed oil and paraffin; placing the sheet in cold water temporarily; then working and crumpling the sheet to soften the same; then, while the sheet is still damp, successively pressing said sheet and said stencils together to emboss the design on said sheet; then spreading the sheet on a flat surface to dry; and then giving the sheet a coat of lacquer before the same is thoroughly dried.

7. The method of producing ornamental material which consists in forming a design in color upon a sheet of parchment paper by use of a plurality of stencils and lacquer enamels; soaking said sheet in a solution of boiled linseed oil and paraffin; placing the sheet in cold water temporarily; then working and crumpling the sheet to soften the same; then, while the sheet is still damp, successively pressing said sheet and said stencils together to emboss the design on said sheet; then spreading the sheet on a flat surface to dry; then applying a coat of melted glue to the back of the sheet; and then applying a coat of lacquer to said sheet.

8. The method of producing ornamental

material which consists in forming a design in color upon a sheet of parchment paper by the use of a plurality of stencils and lacquer enamels; soaking said sheet in a solution of boiled linseed oil and paraffin; placing the sheet in cold water temporarily; then working and crumpling the sheet to soften the same; then, while the sheet is still damp, successively pressing said sheet and said stencils together to emboss the design on said sheet; then spreading the sheet on a flat surface to dry; then giving the sheet a coat of lacquer before the same is thoroughly dried; then spraying said sheet with an antique color mixture of raw umber, turpentine and Japan dryer, and permitting the same to partially dry; then rubbing off some of the coat of antique color; then, while said last-mentioned coat is still wet, rubbing rotten stone powder over the surface thereof; then wiping off said surface; and then permitting said sheet to dry for use.

9. The method of producing ornamental material which consists in forming a design in color upon a sheet of parchment paper by the use of a plurality of stencils and lacquer enamels; soaking said sheet in a solution of boiled linseed oil and paraffin; placing the sheet in cold water temporarily; then working and crumpling the sheet to soften the same; then, while the sheet is still damp, successively pressing said sheet and said stencils together to emboss the design on said sheet; then spreading the sheet on a flat surface to dry; then applying a coat of melted glue to the back of the sheet; then applying a coat of lacquer to said sheet; then spraying said sheet with an antique color mixture of raw umber, turpentine and Japan dryer, and permitting the same to partially dry; then rubbing off some of the coat of antique color; then, while said last-mentioned coat is still wet, rubbing rotten stone powder over the surface thereof; then wiping off said surface; and then permitting said sheet to dry for use.

In witness whereof, I have hereunto set my hand this 18th day of May, 1929.

FREDERICK D. PENNEY.
